Primary Examiner — Cathy Anne MacCormac*(74) Attorney, Agent, or Firm* — Global IP Counselors, LLP(57) **CLAIM**

The ornamental design for a litter container, as shown and described.

DESCRIPTION

FIG. 1 is a top perspective view of a litter container in accordance with our new design;

FIG. 2 is a top view thereof;

FIG. 3 is a front view thereof;

FIG. 4 is a back view thereof;

FIG. 5 is a left side view thereof; and,

FIG. 6 is a bottom view thereof.

The broken lines depict environmental subject matter, are for illustration only, and form no part of the claimed design. The broken lines that are immediately adjacent to the shaded areas and define unshaded regions represent the bounds of the claimed design. The broken lines that are shown within the broken line boundaries and the broken lines outside of the claim are directed to environment. The broken lines form no part of the claimed design.
